CLAIM

(51) **LOC (10) Cl.** **14-03**

The ornamental design for a “knob for speaker,” as shown and described.

(52) **U.S. Cl.**

USPC **D14/221**; D14/204

DESCRIPTION

(58) **Field of Classification Search**

FIG. 1 is a perspective view of knob for speaker showing our new design; and,

CPC H04M 1/03; H04M 1/035; H04R 1/02;
H04R 1/06; H04R 1/021; H04R 1/025;
H04R 1/026; H04R 1/105; H04R 1/323;
H04R 1/345; H04R 1/403; H04R 1/2803;
H04R 1/2834; H04R 5/02; H04R 7/20;
H04R 9/06; H04R 9/025; H04R 2201/021;
H04R 2400/07; H04R 2499/11; H04R
2499/13; H04R 2499/15; G06F 1/1688;
H04N 5/642; H04N 21/4852; H04S 3/00;
H04S 7/30; B60R 11/0217

FIG. 2 is a top view thereof.

USPC D14/167, 168, 170–172, 188, 194–197,
D14/204, 207, 209.1, 210–217, 221, 222,
D14/224, 238.1, 432, 454–456, 496,
181/143, 144, 147, 148, 150, 153, 157,
181/198, 199; 381/300–303, 306, 332, 333,

The broken line showing of a speaker is included for the purpose of illustrating environment of the design and forms no part of the claimed design.
